ATTORNEY

UNITED STATES PATENT OFFICE

CHARLES TIETZMANN, OF DAYTON, OHIO

LIGHT REFLECTOR AND THE LIKE

Application filed January 28, 1929. Serial No. 335,531.

This invention relates to improvements in light reflectors, having particular reference to reflectors for automobile instrument board lights.

5 The object attained by the invention consists of a simple, inexpensive reflector that can be attached to automobile instrument board lights commonly used, without making changes in the original light assembly, and 10 without the use of tools.

The improved reflector is a popular priced accessory that will readily fit any automobile instrument board light, that can be attached by the purchaser, that will reflect the 15 light more effectively over the usual instruments, such as the speedometer, gasoline, and oil pressure gauges, etc., and that can be adjusted to the varied arrangement of the instruments so that the light will be reflected 20 to best advantage.

In the accompanying drawings which serve for illustrating the invention:

Fig. 1 is a front view of the reflector;

Fig. 2 is a view in side elevation of an instrument board light assembly including the reflector;

Fig. 3 is a plan view of the reflector.

As shown in Fig. 2, the light assembly is supported on an instrument board of an automobile, indicated by the dotted line 1, the light 2 being enclosed in a common light guard 3 having the usual openings 4—5—6 and reflector 7 for directing the light upon the instrument board and to the floor of the 35 machine. Devices of this character are more or less unsatisfactory as the light is too diffused for adequate illumination of the instruments, also shadows are cast which tend further to ineffective lighting.

40 For correcting this condition and effecting more adequate lighting of all the instruments which require observation in driving an automobile, the reflector 8 herein set forth is attached to the base of the instrument board 45 light, illustrated by light 2, and acts to reflect

the light passing upward through aperture 6 directly upon the main instruments.

To this end the reflector consists of opposite spring tensioned fingers 9 which engage the light base frictionally on opposite sides 50 for supporting the reflector in any position of adjustment, the arms 9 being free to rotate on the light base. An arm 10 extends upward and outward from parts 9 at an angle for supporting the reflector plate 11 at the 55 required elevation for directing the light as desired upon the instruments, the light striking the reflector through an aperture 12 in arm 10. The reflector face of part 11 is highly polished or plated for making it effective.

The angle of reflector plate 11 relative to arm 10, and of arm 10 relative to parts 9, can be varied by bending the metal for reflecting the light to best advantage according to 65 the arrangement of the instruments.

The reflector will also be effective for lighting the instrument board without the light guard 3. When so used, part 10 will be wider and concavical, preferably, on its under 70 side for serving as a lateral shield for the light.

I claim as my invention:

1. A reflector for an instrument board lamp consisting of a friction clip for attaching the 75 reflector detachably to the base of the lamp, an arm extending outward and upward from said clip and having an aperture over said lamp, and a reflector extended upward outwardly adjacent said aperture for directing 80 light that passes through said aperture from said lamp onto the instrument board.

2. A reflector for an instrument board lamp consisting of an integral part comprising a friction clip for connecting the reflector detachably to the base of the lamp, an inclined portion extending outward and upward from the clip and having an aperture therein over said lamp, the upper end of the inclined portion being turned upward adjacent said aper- 85 90 95

ture and having a surface that reflects light passing through said aperture from the lamp onto the instrument board.

3. An instrument board lamp including a casing for the lamp having an aperture open upward, a reflector connected detachably and adjustable relative to said casing and having an aperture above the aperture in the casing, and an upwardly extended portion that reflects light from the lamp that passes through said aperture onto the instrument board.

In testimony whereof, I affix my signature.
CHARLES TIETZMANN.
